UNITED STATES PATENT OFFICE.

FRED KNOERR, OF CHICAGO, ILLINOIS.

REFRIGERATING APPARATUS.

1,269,612.

Specification of Letters Patent. Patented June 18, 1918.

Application filed March 23, 1917. Serial No. 156,875.

To all whom it may concern:

Be it known that I, FRED KNOERR, a citizen of the United States, residing at Chicago, in the county of Cook and State of Illinois, have invented a new and useful Refrigerating Apparatus, of which the following is a specification.

This invention relates to refrigerating apparatus.

10 An object of the invention is to provide a compact and efficient combination show case and a refrigerator also having cold storage receptacles and provided with means for producing a circulation of cold air through the show case, whereby temperatures much lower than those heretofore used in refrigerating apparatus of this kind are obtained.

The invention in the present instance resides in the special arrangement of ice tanks 20 and cold storage receptacles within the refrigerator in which they are placed, and in the relation of the fan or blower with reference thereto for creating a current of cold air through the show case.

25 In the accompanying drawings I have illustrated one embodiment of my invention, in which:

Figure 1 is a perspective view of the apparatus.

30 Fig. 2 is a plan view of the same with the top of the show case removed and with the cover of the refrigerator thrown back.

Fig. 3 is a rear elevation of the same.

35 Fig. 4 is a longitudinal sectional view on the line 4—4 of Fig. 2, looking in the direction of the arrow.

Fig. 5 is a transverse sectional view on the line 5—5 of Fig. 4, looking in the direction of the arrow.

40 Fig. 6 is a transverse sectional view on the line 6—6 of Fig. 4, looking in the direction of the arrow.

Fig. 7 is a diagrammatic view of the electrical connections for the motor used in driving the fan.

45 In the embodiment here illustrated, there has been provided a suitable show case or show counter 1 having a transparent front 2 preferably of glass in order that the goods 50 may be inspected and provided at the rear with suitable doors 3 whereby access may be had to the same.

55 Abutting one end of the show case 1 is the combination refrigerator, freezer and cold storage cabinet 4, provided with a hinged cover 5 at the top and a suitable door 6 at

one end, whereby access may be had to the various tanks and receptacles therein. Within the cabinet 4 and resting upon the bottom thereof is a drip pan 7. Mounted 60 upon the drip pan is a reticulated grating 7^a for supporting the tanks or receptacles about to be described, so that they will not interfere with the free circulation of air from the cabinet to the show case and back 65 again.

Spacing blocks 8 are arranged within the cabinet 4 at the upper edges of the front and rear walls thereof. Tanks 9 rest upon the grating 7^a and are spaced from the front 70 and rear walls the width of the spacing blocks 8, whereby downwardly extending passages 10 are provided between the tanks 9 and said front and rear walls. As is clearly shown in Fig. 2, these tanks are 75 spaced slightly from the wall of the cabinet adjacent to the show case. Within the tanks 9 are auxiliary tanks 11 arranged against the central portions of the inner walls and attached to these walls by means of clips 12. 80

Arranged between the tanks 9 and resting upon the grating 7^a is a cold storage receptacle 13 open at one side, as indicated at 14 and arranged behind the door 6 whereby access may be had to the receptacle when 85 the door is open. The wall 15 of the receptacle 13 is spaced a substantial distance from the side of the cabinet 4 adjacent to the show case providing a space 16 between the same and said side. 90

Resting upon the upper end of the receptacle 13 is a second cold storage tank or receptacle 17 open at one side, as indicated at 18, and facing the door 6 whereby access may be had to the same when the door is 95 open. The top 19 of the receptacle 17 is closed while its vertical wall 20 is in alignment with the vertical walls at that side of the tanks 9 and is also spaced from the wall of the cabinet 4 adjacent the show case. The 100 cold storage receptacle 17 is retained in position by means of clips 22 which engage the upper edges of the tanks 9 as clearly shown in Fig. 2. Shelves may be provided in the receptacles 13 and 17, as shown. 105

Mounted in the space between the tanks 9 and receptacle 17 and the wall of the cabinet adjacent to the show case is a cold air tank 23, which fills the entire upper half of the above-mentioned space. Between the 110 lower portions of the tanks 9 and the wall adjacent to the show case and below the

tank 23 is mounted a fan or blower 24. This fan faces the wall 15 of the lower cold storage receptacle 13 and is adapted to draw cold air from the cold air space 16 and to 5 deliver it through a pipe 25 to the cold air tank 23. The fan is operated and controlled by a motor 26 which may be located in any suitable position inside or outside of the cabinet and which is here shown as mounted 10 upon the inside within the space 16. Mounted upon the rear of the cabinet 4, as shown in Fig. 3, is a suitable switch or rheostat 27 interposed in a circuit 28 connected with the motor and with a suitable source of power 15 29, as shown in Fig. 7. The switch or rheostat is for the purpose of controlling the speed of the motor and also for starting and stopping the same.

A thermostat 30 is also interposed in the 20 circuit 28 and may be located in any suitable position within the show case or refrigerating cabinet, but is here shown, for the purpose of illustration, mounted in the upper inner end of the show case 1. A suitable 25 indicator and regulator 31 is connected in any suitable manner with the thermostat and is mounted upon the rear of the show case, as shown in Fig. 3.

The cold air tank or chamber 23 communicates by means of short pipes 32 with the interior of the show case. These pipes 32 enter the upper part of the show case at one end thereof. Pipes or conduits 33 are connected to and communicate with the short 35 pipes and extend across the show case to the opposite end thereof, where they are supported and closed as indicated at 34. The pipes 33 are provided with a plurality of openings 35 upon their lower sides whereby 40 the cold air is driven by means of the fan into the show case. As the air within the show case warms, it ascends and escapes through pipes or conduits 36 provided with openings communicating with the passages 45 10 and located immediately below the spacing blocks 8. The air in descending the passages is again cooled and returned to the refrigerator.

The drip pan 7 serves to receive the drippings 50 from the frost which is deposited upon the tanks and receptacles within the cabinet 4 and is provided with a suitable drain pipe 37. The tanks 9 are also provided at the lower ends thereof with faucets 38 for regulating the height of water within the same.

The tanks 9 above described are intended 60 to be filled with ice with which is mixed a salt, such as ammonium nitrate, calcium chlorid or sodium chlorid, or any salt which will absorb heat when dissolved. It will be seen that by mixing a salt with the ice in the receptacles or tanks 9 a very low temperature can be obtained. The tanks 9 are arranged at each side of the cold storage receptacles 13 and 17 so that the latter will be

maintained at a very low temperature. The tanks 11 are adapted to receive pure or distilled water, and as the ice in the tank 9 melts, ice will form in the tanks 11. It will, therefore, be seen that my apparatus has 70 means for the replenishment and maintenance of its cold producing medium.

Another feature of the invention which serves to still further lower the temperature resides in the fan 24 mounted in the inner 75 lower portion of the cabinet 4 to the rear of the space 16. This space, it should be noticed, is fully protected and lies between the tanks 9, which are to be, as pointed out, at a very low temperature. The extremely 80 cold air, within the space 16 will be drawn into the fan up into the cold air chamber 23 and then blown through the pipes 33 into the show case. As the air warms therein, it will return through the short pipes 36 85 down through the passages 10 where it cools by reason of the adjacent tanks 9, through the drip pan 7 and grating 7^a, up into the space 16 where it becomes cold as before, and the operation is repeated.

The fan operating in the refrigerator serves to cause a continuous circulation of the air within the show case 1, thus resulting in a thorough distribution of the chilled atmosphere and maintaining a very low temperature 95 therein.

As here shown the motor and fan or blower are placed upon the inside of the cabinet or refrigerator 4 and are arranged with relation to the tanks and receptacles so that they 100 will not come in contact with the same. The motor is controlled by means of the switch whereby the temperature within the show case can be regulated and it is also preferable to provide the automatic control or thermostat for maintaining the temperature within the show case constant and definite.

My invention is not intended to be limited to a show case as it is applicable to refrigerators, ice-boxes, and cold storage rooms of 110 all kinds.

While I have shown and described one embodiment of my invention, it is to be understood that I do not desire to be limited to the details of construction herein shown and described, for obvious modifications will be apparent to anyone skilled in the art.

What is claimed is:

1. In a refrigerating apparatus, a cabinet containing tanks spaced from the bottom 120 thereof adapted to contain ice or a freezing mixture and having therebetween a cold air space, a blower in said cold air space, a show case, a conduit connecting said blower with said show case, said tanks being spaced from opposite walls of said cabinet providing passages, and conduits connecting said show case with the passages.

2. In a refrigerating apparatus, a cabinet containing a pair of spaced apart tanks 130

- adapted to receive ice or a freezing mixture, cold storage receptacles mounted between said tanks and providing therewith a central cold air space, a show case, a blower mounted 5 within said cabinet adjacent to said cold air space and communicating with said show case, the walls of said cabinet and said tanks forming passages, and return conduits connecting said show case with said passages.
- 10 3. In a refrigerating apparatus, a cabinet, a grating located at the bottom of said cabinet, a pair of tanks adapted to receive ice or a freezing mixture mounted within the cabinet and spaced apart, a cold storage receptacle resting upon said grating and located between said tanks, a second cold storage receptacle mounted above said first-mentioned receptacle and extending beyond the end thereof providing a cold air space 15 between the tanks and said receptacles, a show case, a blower within said cabinet adjacent to said space, and conduits connecting said blower with said show case.
- 20 4. In a refrigerating apparatus, a cabinet containing a pair of tanks adapted to receive ice or a freezing mixture, and spaced from each other and from three walls of said cabinet providing passages between the tanks and certain of the walls for the circulation 25 of air, cold storage receptacles mounted between the tanks, means for gaining access to said cold storage receptacles, means for gaining access to said tanks, means for spacing said tanks and receptacles from the bottom of the cabinet providing a bottom passage, said tanks and receptacles providing 30 between the same a central space communicating with said side and bottom passages, a show case, and a blower mounted in said cabinet adjacent to said central space and adapted to blow cold air into said show case.
- 35 5. The combination with a show case, of a refrigerator comprising a cabinet adjacent to said show case, tanks within said cabinet spaced from each other and from certain 40 of the walls of the cabinet forming passages communicating with the show case, cold storage receptacles mounted between said tanks, a drip pan within the bottom of the cabinet, a reticulated grating mounted upon 45 said drip pan for supporting the tanks and receptacles, the lower of said receptacles being spaced a substantial distance from the wall of the cabinet adjacent to the show case,
- 50 55 providing a cold air space therein, a cold air tank interposed in the upper end of said cabinet between said tanks and the upper of said receptacles and the wall of the cabinet adjacent to the case, a blower or fan 60 mounted within said cabinet below said cold air tank and connected to the latter, and a connection between said cold air tank and said show case whereby cold air is driven from said space into the show case and returned through said passages and up 65 through the grating back into the cold air space.
6. In a refrigerating apparatus, a cabinet having a grating resting upon the bottom thereof, a pair of spacing blocks at the upper edges of a pair of opposed walls of said cabinet, tanks adapted to receive ice or a freezing mixture mounted in said cabinet and spaced apart providing passages between the tanks and the opposite walls below 70 said spacing blocks, a cold storage receptacle resting upon said grating between said tanks and of a width less than said tanks, a second cold storage receptacle mounted between the tanks above said first receptacle, and of a 75 width substantially equal to that of said tanks whereby a central cold air space is provided between the tanks and below said second receptacle, a cold air tank mounted within said cabinet between said tanks and upper receptacle and another wall of said cabinet, a blower mounted within the cabinet below said cold air tank and communicating with the latter and with said central cold air space, a show case, and conduits 80 connecting said show case with said cold air tank and with said passages.
7. In a refrigerating apparatus, a cabinet containing a pair of tanks spaced from each other and from a pair of opposite walls providing side passages between the same and the walls, means for supporting said tanks spaced from the bottom forming a bottom passage communicating with the side passages, cold storage receptacles of unequal 85 size mounted within the cabinet between the tanks and forming therewith a central cold air space communicating with the bottom passage, a cold air tank mounted in the upper portion of said cabinet between said 90 tanks and another wall of the cabinet, a blower mounted below said cold air tank adjacent to said central air space, a show case, conduits connecting said cold air tank with said show case whereby cold air can be 95 forced into the same, and return conduits connecting said show case with said side passages.
- In testimony that I claim the foregoing as my own, I have hereto affixed my signature 100 in the presence of two witnesses.
- FRED KNOERR.
